Attorney

UNITED STATES PATENT OFFICE.

HARVE MARCUM, OF BOONEVILLE, KENTUCKY, ASSIGNOR OF ONE-HALF TO RUTHERFORD B. ROBERTS, OF HAZARD, KENTUCKY.

GRAPPLING TONGS.

Application filed May 29, 1922. Serial No. 564,356.

To all whom it may concern:

Be it known that I, HARVE MARCUM, a citizen of the United States, residing at Booneville, in the county of Owsley and State of Kentucky, have invented certain new and useful Improvements in Grappling Tongs, of which the following is a specification, reference being had to the accompanying drawings.

10 Difficulty has been experienced in fishing or getting various articles or objects out of bored wells, therefore, it is the purpose of the present invention to provide a device of the present character, adapted to be lowered into a well, regardless of its depth, for grasping objects or articles, and then drawing or lifting them out.

To accomplish this result the present device comprises a pair of members pivoted together at their point of intersection and provided with grappling forks, which when the device is lowered it will grapple or grip the object or article, and hold it firm until it is lifted or drawn from the well, in combination with means operatively connecting the other ends of the members, for operating the grappling forks, in order that they may grip the article or object.

Another purpose is the provision of a link pivoted to one of the grasping members and sliding through an eye of the other grasping member, so that by the manipulation of a pair of ropes (which are connected to the eye and the link) the grappling forks may be opened and closed. In fact the forks when the device is lowered into the well may be first opened, to grapple the article or object, after which one of the ropes may be actuated to pull upon the link, which in turn will cooperate with one of the members for closing the grappling forks.

A further purpose is the provision of teeth upon the inturned terminals of the prongs of the grappling forks, to insure a firm grip upon the object or article to be lifted from the bored well.

It is to be understood that the particulars herein given are in no way limitative and that while still keeping within the scope of the invention, any desired modifications of detail and desired proportions may be made in the apparatus according to circumstances.

The invention comprises further features and combination of parts, as will be herein-

after set forth, shown in the drawings and claimed.

In the drawings:

Figure 1 is a view in perspective showing the grappling device in a position lowered in a well, showing the grappling forks open, and the link disposed, so that when manipulating one of the ropes, the forks may close;

Figure 2 is a similar view showing the grappling forks partly closed on an article, the link having been actuated to effect the closing operation of the forks.

Referring to the drawings, 1 and 2 designate two members, of elongated form, which are pivoted together at their point of intersection, as indicated at 3. These members have jaws 4, which are in the form of grappling forks or tongs 5. The prongs of both grappling forks or tongs have their terminals extended toward each other, as shown at 6, and these extensions 6 are provided with teeth 7, to insure a firm grip of the forks upon the article or object to be lifted from the well.

The member 1 has a shank 8, in an eye 9 of which, the eye 10 of a link 11 is pivoted. This link 11 is curved or of arcuate shape, and has an eye 12 at its other end. The link 11 slidably operates through an eye 14, which is integral with the shank 15 of the member 2.

A rope or cable or the like 16 is connected to the eye 12 of the link 11, while a second cable or rope 17 is connected to the eye 14 of the shank 15 of the member 2. Obviously when the grappling device is lowered into a bored well, the cable or rope 17 is held taut, until the prongs of the grappling fork of the member 2 contact with the bottom of the well, or contact with a portion of the object or article to be lifted. The rope 16 is allowed to slack, and by vibrating the cable or rope, the member 1 will tilt sufficiently upon its pivot with the member 2, so as to arrange its fork in an open position, in which case the eye 12 will assume a position adjacent the eye 14, as shown in Figure 1. The cable or rope 17 is then allowed to slack, whereas a pulling action is imparted upon the rope or cable 16, which will actuate the link 11, and due to its curvature or arcuate shape, the link will cam through the eye 14, and cause the grappling forks or tongs to grip the object or article to be lifted from

the well. A continuous pulling upon the cables, a greater tension being exerted upon the cable 16 to keep the grappling forks or tongs closed upon the object, will enable the 5 article or object to be drawn from the well.

The invention having been set forth, what is claimed is:—

1. A grappling device comprising a pair of crossed members pivotally united at their 10 point of intersection, the corresponding end portions of the members terminating in grappling forks, the prongs of the forks having gripping teeth, the shank of one member having an eye, and a link pivoted to the 15 shank of the other member and adapted to operatively clamp through the eye of said one member for actuating the members to cause the forks to grapple an object, and means for actuating the link.
20. 2. A grappling device comprising a pair of crossed members pivotally united at their point of intersection, the corresponding jaws of said members having grappling means for grappling an object or article to be lifted 25 from a well, an arcuate link pivoted to the

shank of one member and cooperatively connecting with the terminal of the shank of the other member for a clamping action, whereby upon applying a pulling or lifting action upon the link, the grappling means 30 may be drawn toward each other in grappling engagement with an object or article to be lifted.

3. A grappling device comprising a pair of intersecting members, means for pivotally uniting said members at their point of intersection, said members having their corresponding end portions provided with grappling means, the shank of one member having an eye, an arcuate link pivoted to the 35 terminal of the shank of the other member and having a sliding engagement with said eye, whereby upon a pull exerted upon the link, a clamping action of the link through the eye is created, for causing the grappling 40 means to grip the article to be lifted.

In testimony whereof I hereunto affix my signature.

HARVE MARCUM.
